UNITED STATES PATENT OFFICE.

JAMES MILLSAP, OF DE SOTO, MISSOURI.

MAIL-BAG DELIVERER.

No. 874,225.

Specification of Letters Patent.

Patented Dec. 17, 1907.

Application filed October 17, 1907. Serial No. 397,840.

To all whom it may concern:

Be it known that I, JAMES MILLSAP, a citizen of the United States of America, residing at De Soto, in the county of Jefferson and State of Missouri, have invented new and useful Improvements in Mail-Bag Deliverers, of which the following is a specification.

This invention relates to mail bag deliverers, and one of the principal objects of the same is to provide means whereby mail bags may be delivered by means of compressed air, fed to a cylinder and released automatically at points where it is desired to deliver a mail bag and to provide discharge tubes into which the bags are placed, one of said tubes being located upon each side of the car, and the outer end of which is open to permit the bag to pass out.

Another object of the invention is to provide means for automatically discharging mail bags from a mail car by means of compressed air.

These and other objects may be attained by means of the construction illustrated in the accompanying drawing, in which:—

Figure 1 is a vertical sectional view taken through a mail car and through the delivery mechanism. Fig. 2 is a perspective view of the trigger connected to a post at the point desired to discharge a mail bag, said trigger adapted to engage the end of a lever for releasing a piston to discharge the bag. Fig. 3 is a sectional view of a check valve connected to the compressed air pipe.

Referring to the drawing for a more specific description of my invention, the numeral 1 designates a mail car, underneath the floor of which is supported a compressed air cylinder 2, to which an outlet pipe 3 is connected, said outlet pipe being provided with a spring-seated check valve 4 comprising a valve casing having a central partition 5 through which the valve stem projects and a valve head 6 adapted to normally close the opening in the partition 5 by means of the stress of spring 7 which bears against the partition at one end and against a head or disk 8 at its other end. The pipe 3 is supported in brackets 9 at the side of the car and is provided with a horizontal branch 3^a which leads to the center of a cylinder which controls the compressed air for discharging the mail bags.

The cylinder 10 has connected thereto near its opposite ends a discharge tube 11,

said discharge tubes being connected to the cylinder by a series of bolts 12 and said tubes having enlarged outer ends which pass through the opposite sides of the car and are provided with hinged doors 13 by means of which the mail bags may be placed within said tubes with the heads of said bags practically filling the circumferential space of said tubes. Mounted in the cylinder 10 are a pair of pistons 14, the piston rods of which pass through the cylinder heads and are connected to levers 16 pivoted at 17, said levers being designed to operate the pistons by hand to set them in the required position to discharge the bags. 70

A series of jet openings or perforations 18 is formed in each end of the cylinder 10 and disposed inside the discharge tube 11. Levers 19, each provided with a pivoted stop pin 20, passing through the discharge tubes 11 and designed to engage one of the jet openings 18, are pivoted at 21 to brackets 22 rising from the tubes 11. The outer ends 23 of the levers 19 extend out through openings 24 in the sides of the car near the roof 80 thereof.

At each station, or point at which it is desired to discharge a mail bag, a post 25 is secured, and near the upper end of said post is a trigger 26 having a downwardly extending 85 arm 27 and a curved terminal end 28 which lies in the path of the outer end 23 of the lever 19.

The operation of my invention may be briefly described as follows: A mail bag to be delivered is placed in each of the tubes 11 through the door 13, and said door is then closed. The pistons 14 are adjusted by means of the lever 16 to the position shown at the left-hand side of Fig. 1, and the pin 20 95 is inserted in the inner end of the apertures 18.

Referring now to the left-hand side of Fig. 1, should a trigger 26 come into contact with the lever 23, said lever would be depressed at 100 its outer end and the pin 20 withdrawn from the cylinder 10. The result would be that the pressure of the compressed air within the cylinder 10 would move the piston 14 to the position shown at the right-hand end in Fig. 105 1. The compressed air would then escape through the openings 18 into the tube 11 upon that side operated and would force the mail bag out, as will be understood. Then the mail bag for the next station is inserted 110

in the tube 11 through the door 13 and the piston 14 again set in the position shown at the left-hand side of Fig. 1.

From the foregoing it will be obvious that by means of my construction, mail bags are automatically discharged from the mail car at the point desired and that a platform or suitable casing may be provided for receiving the bags, if required.

10 My invention is of simple construction, cannot readily get out of order, will operate smoothly under varying conditions, can be located at one end of a mail car out of the way and can be quickly installed for use.

15 Having thus described the invention, what is claimed as new, is:—

1. A mail bag deliverer comprising a cylinder, pistons mounted in said cylinder, discharge tubes connected to said cylinder, 20 pistons in said cylinder, locking pins for holding said pistons in one position, levers connected to said pins and extending out through the arc, and a compressed air reservoir connected to said cylinder between said

25 pistons.

2. In a mail bag deliverer, a cylinder, pistons in said cylinder, discharge tubes connected to said cylinder, a compressed air res-

ervoir connected to said cylinder between said pistons, and means for discharging air 30 from the cylinder to said tubes.

3. In a mail bag deliverer, the combination of a cylinder, pistons in said cylinder, means for locking said pistons, a lever connected to said means and extending out 35 through openings in the sides of the car, a compressed air reservoir leading to the cylinder between the pistons, and a post and trigger for operating the levers for discharging air from the cylinder to the tubes to deliver 40 mail bags.

4. In a device of the character described, a cylinder, discharge tubes connected to said cylinder, a compressed air reservoir communicating with said cylinder, pistons in the 45 cylinder, discharge tubes connected to the cylinder, and means for admitting the air from said cylinder to said tubes for discharging mail bags.

In testimony whereof I affix my signature 50 in presence of two witnesses.

JAMES MILLSAP.
